Primary Examiner — Holly Baynam(74) *Attorney, Agent, or Firm* — Stetina Brunda Garred & Brucker(57) **CLAIM**

The ornamental design for a drawer slide closing mechanism, as shown and described.

DESCRIPTION

FIG. 1 is a front perspective view of the drawer slide closing mechanism of the present invention showing our new design, with the dotted lines depicting environmental structure and forming no part of the claimed design;

FIG. 2 is a opposite side perspective view thereof;

FIG. 3 is a top plan view of FIG. 1;

FIG. 4 is an elevational view of FIG. 1;

FIG. 5 is bottom plan view of FIG. 2;

FIG. 6 is a side elevational view of FIG. 2;

FIG. 7 is left end view of FIG. 6; and,

FIG. 8 is a right end view of FIG. 6.

The broken lines showing portions of the drawer slide are for the purposes of illustrating environment and form no part of the claimed design.
